MOVABLE SUPPORT

Joseph R. Thomas, Chicago, Ill.

Application June 14, 1937, Serial No. 148,159

5 Claims. (Cl. 155—61)

This invention relates in general to a mechanical gliding carrier in which a relatively fixed support is connected to a movable support by members which provide for a substantially level movement or a movement in which the position of the movable member may be slightly raised at the ends of its travel or intermediate the ends thereof.

An important object of the invention is in the provision of mechanical means for providing a gliding movement between relatively fixed and movable members such that the movable member may be maintained substantially in the same plane without sliding, rolling or frictional engagement between the parts.

A further object of the invention is in the provision of a mechanical gliding movement in which a movable member is supported entirely from the under or covered side by the fixed member.

A still further object of the invention is to provide improved means for controlling the movement of the fixed and movable members.

Other objects of the invention will appear hereinafter, the preferred embodiments of the invention being described in the specification and shown in the accompanying drawings in which

Fig. 1 is a side elevation of one form of a mechanism embodying the principles of this invention;

Fig. 2 is an end elevation of the structure shown in Fig. 1;

Fig. 3 illustrates a modification of the structure shown in Fig. 1 with a co-ordinating link;

Fig. 4 is a side elevation showing a modified form of link connection;

Fig. 5 is a side elevation of another form of gliding movement having means for holding the movable part in different positions with respect to the fixed part;

Fig. 6 is a fragmentary front elevation showing the locking means of Fig. 5;

Fig. 7 is a fragmentary plan view showing the locking means of Fig. 5;

Fig. 8 is a side elevation of a modified gliding structure;

Fig. 9 is a view in elevation of the front linkage of Fig. 8; and

Fig. 10 is a view in elevation of the rear linkage of Fig. 8.

For certain carriers and supports it is desirable to provide a controlled gliding movement which is neither rolling nor sliding and in which the movement of one of the members may be in the same plane throughout its travel or the movable member may dip at the center or at the ends of one or both limits of its travel. A controlled gliding movement of this kind may be used for

supporting files, drawers, extending tables or drawing boards, and may be used in a variety of other structures where rolling and slideable connection between the fixed and movable parts is objectionable or undesirable.

Referring now more particularly to the drawings, this invention is disclosed in connection with fixed and movable members in which the connections between them are generally reversible or invertible without requiring any particular change. That is, although one part is described as the fixed part and the other as movable thereto, the movable part may be fixed in position and the other part which was regarded as fixed may be movable with respect thereto without any change in the connecting means.

In the structure shown in Figs. 1 and 2 a lower frame comprising a base member 10, a top 11 and uprights 12, is reported as supported on a fixed plane at the bottom. A member 14 represented as an angle bar positioned above the level of the top 11 is supported from the top by a depending intermediate supporting structure comprising two sets of links 15 and 16, and a plate 17 to which they are pivoted. Each plate 17 is shown as triangular in form having a pivot 18 for mounting it in connection with the member 14, a pivot 19 at one lower angular corner to which one end of a link 15 is pivoted, the upper end of this link being connected by a pivot 20 with the top 11 of a fixed support. The other link 16 is connected by a pivot 21 with the lower opposite corner of the plate 17 and by a pivot 22 at the upper end with the top 11, the distance apart of the pivots 20 and 22 being greater than the distance apart of the pivots 19 and 21.

By having a supporting structure of this kind between the fixed and movable members at the ends of the movable member it is supported for a relative swinging movement of a considerable extent, substantially parallel to the base or fixed member, the movement depending upon the lengths of the links and plates, the distance apart of the pivots 19 and 21 and the pivots 20 and 22 respectively. Substantially the same result may be obtained by attaching the links 15 and 16 to the movable member 14 and the plate 17 to the fixed member, by changing the lengths of the suspension members if necessary. In this connection it is also pointed out that if the member 14 is fixed in position the movement of the base 10 with respect to it would be substantially the same in direction and extent.

Instead of two plate structures at both ends of a movable member as in Fig. 1, a movable mem-

ber 30 may be provided (see Fig. 3) with a plate 17 and links 15 and 16 as shown in Fig. 1, at one end and a pair of links 31 and 32 at the other end. One of the links 31 has a pivot 33 at its upper end connecting it to the member 30, the other link 32 has a pivot 34 at its upper end connecting it to the top member 11 of the frame, and the lower ends of both links are connected by a pivot 35. One of the links 32 is connected by a co-ordinating bar 36 with the plate 17, pivots 37 and 38 at the ends of the bar being located to limit the swinging movement of the member 30.

In the structure shown by Fig. 4 a movable member 40 has a depending link 41 near each end connected to it by a pivot 42, and a link 43 is connected by a pivot 44 at its upper end to the top 11 of the frame, the lower ends of the links being connected together by a pivot 45. In order to limit the movement of this structure, a co-ordinating bar 46 is connected by end pivots 47 to the corresponding bars 41 at the ends of the movable member, and one of the links 43 has an extension 48 beyond its pivot point 45 to which a co-ordinating link 49 is connected at one end by a pivot 50, the other end of the link being connected to the bar 46 by a pivot 51. Thus the limiting movement of the movable member 40 with respect to the fixed frame is controlled and varied, the distance of the pivots 47 from the pivots 42 of the links 41 and the length and connection of the co-ordinating link 49 may be varied to vary the throw and corresponding movement of the member 40.

In all of these forms it will be apparent that the natural tendency of each of the structures is to return to a central or intermediate position, the view shown in Figs. 1, 3 and 4 showing the movable members at one end of their travel for more clearly illustrating the relative positions of the parts.

For some types of gliding structures it may be desirable to lock the fixed and movable parts together at different positions of the movable member. Such a locking structure is shown more clearly in Figs. 5, 6 and 7 but it may be applied equally as well to the other forms of the invention.

A fixed support 55 having an upright frame 56 is located at each end of a support 57 which is movable forward and back to the limiting positions shown by the full and broken outlines in Fig. 5. The swinging support 57 has an angle bar 58 at each end swingingly mounted in the frame 56 by pairs of links 59 and 60 at one end of the bar and 61 and 62 at the other end of the bar. The pairs of links are connected together at their lower ends by pivots 63 and 64 respectively, the pairs are joined by a spacing bar 634 having the same end pivots 63, 64, and the upper ends of the links are connected by individual pivots with the bar 58 and frame 56 respectively.

The pivot 64 of one pair of links may be located at a distance from the lower depending extremity of one of the links and a co-ordinating bar 65 may be connected by a pivot 66 at one end to one of the links 60 and by a pivot 67 at the other end below the pivot 64. To change the throw or travel of the bar 58 and the support 57 the co-ordinating bar 65 is changed in length or in its pivotal connection with the links at either or both ends thereof.

The locking mechanism comprising a plate 70 secured to the upper bar of the frame 56 having an upstanding rim 71 with spaced locking notches 72 in the edge of the rim. A bar 73 is pivotally

mounted at its ends in the angle bars 58 at the ends (only one being shown) of the support 57 and has a crank portion 74 intermediate the ends to which one end of a link 75 is attached, the other end extending through a bracket 76 at the lower front edge of the support where it is easily accessible for movement by simply reaching below the edge of the support. Adjacent each end of the bar 73 and rigidly attached to rotate therewith is a locking pawl 77 adapted to engage in any one of the notches 72 with which it comes in contact. When the link 75 is pulled outwardly from the ledge the latches are raised and when it is pushed inwardly the latches are in position to engage, the natural weight of the latches holding the bar in either position without requiring any spring or other holding means. With the latches in engagement with the corresponding notches at the ends of the frame the movable support 57 is held in fixed position with respect to the supporting frame until the latch is released.

In the modification shown by Figs. 8, 9 and 10, a fixed base 80 has a rear support 81 and a front support 82 extending above and below a movable support 83. The front portion of the movable support is suspended from its under side by links 84 and 85 pivoted together at their lower ends and the upper end of one connected by pivot 86 to the upper end of the support 82 and by pivot 87 to the under side of the member 83. At the rear a link 88 is connected by a pivot 89 to the top of the rear support 81 and by a pivot 90 to the downwardly turned rear extremity 91 of the support 83. To co-ordinate the movement of the front and rear swinging supports and to control the swinging action of the member 83, a bar 92 has a pivot 93 at one end connecting it intermediate the ends of the rear suspending link 88 and a pivot 94 at the other end of the bar 92 may coincide with the pivot joining the front legs 84 and 85. It will be understood that the above structure is located at each end of the member 83 which may be of considerable length to form any sort of a support or even a swinging seat structure, the fixed and movable members being connected by cross pieces 95 and 96 respectively. It will also be understood that the swinging movement is controlled and varied by connecting the ends of the co-ordinating bar 92 at different points along the suspension links to which they are connected. This structure also tends to center itself from either limiting position as shown in Fig. 8.

Although the movable arms and levers are shown at the outside of the fixed uprights, they may be located and similarly connected inside of the uprights. Also the relatively fixed and movable structures shown more particularly in Figs. 1 to 7 may be used in inverted relation, that is, by making the fixed support movable and the movable support the fixed member, without materially altering the connection of the parts. Structures of this kind are particularly adapted for use in filing cabinets, for extensible supports, such as trays, and for end tables and the like. By properly connecting and proportioning the supporting and connecting parts the movable member may move outwardly and then rise at the outer end of its travel, or if desired the movable member may be moved outwardly and then turned upwardly in a vertical direction. Various other variations in the structure and operation may thus be made without departing from the spirit and scope of the invention.

I claim:

1. A stationary base and a seat mounted to glide thereon, the mounting comprising front and rear pairs of swinging links at each end of the seat, the upper ends of the links of each pair being pivoted to the base and seat to swing freely thereon and depending therefrom and pivotally connected to each other at their lower ends, and a rigid coordinating bar extending directly between and pivotally connected at its ends to one of the links of the front and rear pairs at one end of the seat for controlling the extent of swinging movement of the seat.

2. In a mechanical reciprocating level rocking swing, the combination with a stationary base support and a movable seat member, means for connecting the movable seat member to the support to swing substantially in a single plane, said means comprising a plurality of pairs of swinging and supporting means, each comprising a link directly pivoted at its upper end to the support and depending therefrom, and a supporting link member directly pivoted at its upper end to the under side of the swinging seat member and depending therefrom and pivoted at its lower end to the first link, a co-ordinating bar connecting the swinging and supporting pairs of links at the same end of the movable seat member, and means extending from one of the swinging and supporting links to the bar for controlling the extent of movement of the seat member.

3. In a mechanical reciprocating level rocking swing, a stationary upwardly extending support, a member movable thereto, means for mounting the movable member to swing in a plane with respect to the fixed support, said means comprising sets of links at the front and rear of the movable member as determined by the forward and rearward movement thereof, each set comprising a link pivoted at its upper end to the fixed member and depending therefrom, and a supporting link pivoted to the under side of the movable member and pivotally connected at its lower end to the said depending link, and a stabilizing member comprising a bar pivotally

connected at its ends to a link of the front and rear sets and at one side of the pivotal connection between the links at one end, and means connecting the supporting link from the other side of its pivotal connection with its other link to the said bar for controlling the swinging action of the movable member.

4. A stationary base, a seat therefor, means for mounting the seat to swing on the base comprising a pair of links at the front and rear of each end of the seat, one link of each pair pivoted at its upper end to the stationary base and depending therefrom, the other link of each pair pivoted at its upper end to the end of the seat and depending therefrom, the lower ends of the links of each pair being pivotally connected together, a rigid spacing bar pivotally connected at its ends directly to corresponding points on the front and rear pairs of links at the same end of the seat, and a rigid co-ordinating bar directly pivoted to opposite links of the front and rear pairs at the same end of the seat, one end of the latter bar being pivoted to a link above its lower pivotal connection and the other end of the bar being connected to the link below its lower pivotal connection with its companion link.

5. A stationary base, a seat therefor, means for mounting the seat to swing on the base, comprising a pair of links at the front and rear of each end of the seat, one link of each pair pivoted at its upper end to the stationary base and depending therefrom, the other link of each pair pivoted at its upper end to the end of the seat and depending therefrom, the lower ends of the links of each pair being pivotally connected together, and a rigid co-ordinating bar pivoted at one end to one link of the rear pair of links at one side of its pivotal connection with the other link and the other end of the bar being pivoted to the correspondingly opposite link of the front pair of links at the opposite side of its pivotal connection with its other link to control the movement of the seat.

JOSEPH R. THOMAS.
